UNITED STATES PATENT OFFICE.

RICHARD A. WHITTINGHAM, OF NEWARK, DELAWARE.

STEAM-BOILER.

1,368,310.

Specification of Letters Patent. Patented Feb. 15, 1921.

Application filed May 1, 1917. Serial No. 165,735.

To all whom it may concern:

Be it known that I, RICHARD A. WHITTINGHAM, a citizen of the United States, residing at Newark, in the county of New Castle and State of Delaware, have invented certain new and useful Improvements in Steam-Boilers, of which the following is a specification.

This invention relates to steam boilers, 10 and especially to high pressure boilers of the sectional water tube type. More specifically, the invention relates to boilers of the character shown in my Patent Number 1,259,945, dated March 19, 1918.

In addition to the general objects stated 15 in said application, the present invention seeks to provide a construction having certain advantages as to rigidity and strength, as well as improved structural details, as 20 will hereinafter appear, and which coöperate to increase the practical utility and efficiency of the boiler.

In order that the invention may be readily understood, reference is had to the accompanying 25 drawings, forming part of this specification, and in which,

Figure 1 is a typical transverse section through my improved boiler, parts being in elevation; and,

Fig. 2 is a longitudinal vertical section 30 through the same, substantially at the center, parts being in elevation, and other parts being broken away.

Each section of the boiler, in the present 35 invention, comprises a main header consisting of a closed tubular ring, as distinguished from the U-shaped header of my patent above referred to. A seamless drawn tube 1, of suitable size, is bent to form vertical parallel portions 1^a and 1^b, and has its ends united by welding so as to form a completely closed ring. This ring preferably has an apex or highest point 1^c, from which the steam is collected, and a central 40 lowermost point 1^d, into which the water is fed.

The auxiliary or central header of each section consists of a pair of straight, parallel, vertically disposed tubular members 50 2 and 3, closed at their ends. These members may be wholly independent, but are preferably united at their upper ends by means of a U-shaped tube 4, which may be of considerably smaller diameter than the members themselves. This tube while uniting the members 2 and 3, at the same time, per-

mits of relative movement thereof due to expansion and contraction.

Extending between and connecting the header members 1^a and 2 and the header 60 members 1^b and 3, are series of cross tubes 7 and 6, respectively, such tubes being preferably straight and slightly inclined upwardly from the main to the central header, as in my former application.

A steam header 8 extends along the top 65 of the boiler and is connected with the top-most point 1^c of each main header by means of tubes 9 and 10, united by a coupling 11. Inside this header is a steam collecting 70 pipe 12, provided with small perforations throughout its length, in a manner well known in the art. From the pipe 12 extends the main steam pipe 13 to the engine (not shown), the pipes 12 and 13 being connected by a suitable coupling 14.

At the rear of the boiler proper I provide a baffle plate 15 of some refractory material, and behind this baffle plate I arrange a feed water heater or economizer. This is 80 similar in construction to that shown in my former application and comprises a series of tubular headers 16, provided with cross tubes 19, around which the products of combustion flow after passing over the 85 baffle plate 15.

Water is supplied to the boiler through a pipe 21, which is connected by taps 22 to the various sections of the economizer. From the economizer the heated water flows 90 through pipe 24 to the water main 25, which extends centrally underneath the boiler. The lowermost point 1^d of the main header of each boiler section is connected with the water main 25 by means of pipes 26 and 27, 95 united by a coupling 28, and preferably welded into both the water main and header.

One great advantage of constructing the main header members in the form of closed tubular rings is that such a configuration 100 enables the headers to withstand enormous steam pressure without danger of deformation or distortion. Another very desirable feature of this construction is that the lower portions 5 of the ring-shaped headers form 105 a floor on which the burner or heat generator can be supported. In the drawing I have shown conventionally a liquid fuel burner 29 of a well known type, preferably formed of two sections and shaped to conform to 110 the curvature of the lower portions 5 of the header members. It will be seen that this

burner is entirely inclosed within the ring-shaped headers and rests upon the same in such a way that it can be withdrawn, after the manner of a cabinet drawer. The burner 5 can thus be readily removed for inspection or repairs without in any way disturbing the boiler, and no supporting means of any kind for the burner, other than the boiler itself, is required.

10 As in my former construction, the steam passes from the central header members 2 and 3 downwardly through the upper tubes 6 and 7 on its way to the outlet pipe 10, and is thereby strongly superheated. The 15 tube 4 permits equalization of pressure between the header members 2 and 3 and, as above stated, admits of free relative movement due to expansion or contraction.

I preferably surround the boiler with a 20 heat insulating lagging 30, covered with a suitable sheathing 31, and the steam header 8 and connecting pipes may be inclosed in a housing 32. These parts have been omitted from Fig. 2 for the sake of clearness.

25 What I claim is:

1. In a boiler composed of vertically arranged sections, a main header composed of a tubular ring, a central header comprising two tubular members extending vertically 30 within the ring, two vertical series of tubes extending between the sides of the ring and said members, respectively, said members being free to move laterally with respect to the ring and to one another when the tubes 35 expand or contract.

2. In a boiler composed of vertically arranged sections, a main header composed of

a tubular ring, a central header comprising two tubular members extending vertically 40 within the ring, two vertical series of tubes extending between the sides of the ring and said members, respectively, and supporting the latter, said members being free to move laterally with respect to the ring and to one another when the tubes expand or contract. 45

3. In a sectional boiler, a section comprising a main header composed of a tubular ring, a central header between the side portions of the ring and comprising two vertically arranged tubes spaced apart, and two 50 series of inclined tubes connected between said side portions and said tubes, the tubes of the central header being movable with respect to one another and to the main header when said inclined tubes expand or contract. 55

4. In a sectional boiler, a section comprising a main header composed of a tubular ring, a central header between the side portions of the ring and comprising two vertically arranged tubes spaced apart and closed 60 at their lower ends, a bent tube connecting the upper ends of said tubes, and two series of inclined tubes connected between said side portions and said tubes, the tubes of the central header being movable with respect 65 to one another and to the main header when said inclined tubes expand or contract.

In testimony whereof I have affixed my signature, in presence of two witnesses.

RICHARD A. WHITTINGHAM.
